(57) CLAIM

I claim the ornamental design for a pocket, substantially as shown and described.

DESCRIPTIONFIG. 1 is a front view of a pocket showing my new design.
FIG. 2 is a rear view thereof.

FIG. 3 is a left side view thereof.

FIG. 4 is a right side view thereof.

FIG. 5 is a top view thereof.

FIG. 6 is a bottom plan view thereof;

FIG. 7 is a front view thereof showing an open upper flap with loop and hook fastening means.

FIG. 8 is a front view thereof, showing an open zipper to a side chamber;

FIG. 9 is a front view thereof showing an open zipper to a side chamber.

FIG. 10 is a front view thereof showing an open zipper to the side chamber an attached to a pant leg; and,

FIG. 11 is another front view thereof, showing the pocket attached to a pant leg.

The broken lines, shown throughout the views in FIGS. 1-11, on the surface of the pockets represent stitching. The remaining broken lines, showing portions of the human form, pants and shirt, show the design in use and form no part of the claim.
